REFRACTORY BLOCK AND STRUCTURE

Mark C. Neil, River Forest, Ill.

Application July 31, 1936, Serial No. 93,551

18 Claims. (Cl. 263—51)

My invention relates to an improvement in liner blocks for stacks and the like and to an improved stack structure formed by said blocks.

Another purpose is the provision of improved 5 means for securing a stack liner in position.

Another purpose is the provision of an improved arrangement of interior ducts in a stack whereby outside air is pre-heated by the heated 10 gases passing through the stack and at the same time serves as means for cooling the stack and the stack lining.

Other objects will appear from time to time in the course of the specification and claims.

I illustrate my invention more or less diagrammatically in the accompanying drawings wherein:

Figure 1 is a vertical section through a stack;

Figure 2 is a section on the line 2—2 of Figure 1;

Figure 3 is a horizontal section through the stack and liner wall, on an enlarged scale;

Figure 4 is a section on the line 4—4 of Figure 3;

Figure 5 is a bottom view of a liner block;

Figure 6 is a detail of a supporting hanger;

Figure 7 is a vertical section taken substantially along the line 7—7 of Figure 1, illustrating the air passages and showing the liner structure;

Figure 8 is a perspective view of one of the block 30 portions; and

Figure 9 is a perspective view of a filler block.

Like parts are indicated by like symbols throughout the specification and drawings.

1 indicates any suitable foundation upon which 35 a stack base structure 2 may be positioned, the details of which form no part of the present invention. 3 indicates the outer shell of the stack herein shown as a cylindrical metal shell. It will be understood, however, that various shapes

40 may be employed, either curvilinear or rectangular in cross section, and that various materials may be employed, such as brick and the like.

4 indicates a hot air collecting header connected to the stack structure by a plurality of air 45 outlet passages 5. 6 is a pre-heated air duct extending from the header 4 to any suitable point of use such as a furnace or the like, not herein shown. A plurality of outside air inlets are indicated in the form of downwardly turned elbows

50 7. The portion of the stack which relates particularly to this invention is the portion extending generally from the header 4 to the inlets 7, which is below described.

8 is any suitable angle iron or abutment for 55 supporting the lining of the upper portion of the

stack, generally indicated as at 9, which may be of cupola block, fire brick, or the like. Referring to that portion of the stack which relates primarily to my invention, I illustrate an air lane generally at 10. This air lane is defined by a 5 plurality of blocks shown in detail for example in Figures 3, 5 and 8. In the particular form of block herein shown, each block consists of two assembled portions, the upper portion generally indicated at A in Figure 7, and Figure 8, and the 10 lower portion indicated at B in Figure 7. Each portion includes an inner face member 15 and an outer face member 16. These two face members are connected by connecting portions 17, for the upper blocks, and 17a for the lower blocks, 15 which combine to form a connector for the assembled blocks which is generally oval or streamlined in vertical cross section, as shown for example in Figure 7.

The inner surface portion 15 is preferably 20 somewhat longer than the outer surface portion 16, as shown for example in Figure 5. In order to provide close joints, I employ tongues 18 and grooves 19, if desired, the tongue and groove structure having the advantage of forming a very 25 tight air lock, especially when the blocks are cemented into place, in such fashion that air from the air lane 10 cannot escape to the interior of the stack, nor can heated gases from the interior of the stack penetrate to the air lane. 30

It will be observed, for example in Figures 3, 5 and 8, that the inner face portion 15 is generally arcuate as is the outer face portion 16, and that the two portions are generally concentric. This is an advantageous form for employment in 35 stacks which are cylindrical or oval in cross section and may be varied to suit the form of the stack in the event that stacks bounded by rectilinear walls are employed.

The rear face portion 16 is provided with shoulders 20 which conform to lateral extensions 22 of the spacer blocks generally indicated at 21 and shown in detail in Figure 9. It will be understood that when blocks of the form shown in Figure 8 are assembled, as in Figure 3, the inner 45 face portions 15 abut against each other and are tightly connected by the tongues 18 and grooves 19 and whatever plaster or cement 24 may be employed to close the joint. The outer face portions 16, however, are spaced apart and this space 50 is closed by the fillers or spacers 21, so that the particular passage or portion of the air line 10 which is defined by any particular group of blocks A and B is completed, on the outside, by the spacer or filler blocks 21. 55

I find it advantageous to support the blocks upon the shell 3 by means of a plurality of hangers as shown for example in Figures 4 and 6. Each hanger, generally indicated at C, includes a base portion 25 which may be bolted to the inner face of the shell 3, for example by bolts 26 and exterior nuts 27. The bolt head may be received in a recess 28 in the base member 25. Extending inwardly from the lower edge of the base 25 I illustrate a shelf portion 29 and a vertical web 30 terminating in a T 31. A further reinforcement 32 may be employed if desired. The structure is preferably a unitary casing of any suitable metal, and is of sufficient strength to support a very substantial weight.

While under some circumstances it may be advantageous to have a hanger for each block, I find that in practice an efficient arrangement is to space the hangers fairly widely apart. I illustrate, for example, in Figure 7 an arrangement in which the hangers are arranged in rows, there being a row of hangers, for example, for every fourth row of blocks, there being a hanger for every alternate block for each such row. It will be understood, of course, that the spacing of said hangers may be varied to suit individual installations. This leaves, as shown in Figure 7, one or more intermediate rows of blocks without hangers. In order to bury the hanger in the mass of the connector 17, and to insulate it from the heated air which passes along the air lane 10, I preferably position the hangers only in the upper portion A of each block.

The blocks which engage the hangers are cored out or apertured to conform to the hanger in shape, as shown for example in Figures 4 and 5. An enlarged bottom aperture 35 receives the shelf 29. A vertical aperture 36 receives the web 30 and the portion 32. It is provided with a cross aperture 37, to receive the T 31. An elongated groove 38 provides clearance for the bolt head of the securing bolt 26. When the block portion is dropped into position upon the hanger, downward movement is prevented by the shelf 29. Lateral movement along the arc of the stack is prevented by the cross piece or T 31. When other blocks are positioned above the blocks so held, it is firmly positioned in relation to the structure. However, referring to the liner as a whole, the weight is supported at a large number of points from the shell of the stack, and cumulative load is prevented.

Assume that the stack shell is in position, the structure given at the bottom and the bottom blocks may be supported directly upon the base portion 2. Each row of blocks is staggered and the blocks are assembled with the filler blocks 21 dropped or positioned in place as shown in Figure 3. Each filler 21, is shown in Figure 4, 60 rests directly upon the top block portion A beneath it, and is covered by the bottom block portion B of the block next above it. The joints may be cemented or plastered in the usual way and since the front portions 15 are shown as 65 connected by a tongue or groove connection 18 and 19, and since the portions 16 and 21 are offset to overlap each other, very tight joints are provided for the air lane 10.

A very advantageous feature of my construction rests in the fact that in the event that any of the blocks burn out or crack, a localized portion of the lining can be removed and separately replaced. The workman in that case preferably knocks out one of the intermediate blocks which 75 is not provided with a hanger. Knocking out

one such block does not loosen or release the blocks above it, as there is a bridge or arch effect between adjacent hangers. For example, if the block marked X in Figure 7 were removed, the blocks Y and Z above it are still supported 5 by the adjacent hangers, and the intermediate filler block 21, gripped between the blocks Y and Z, is presumably still cemented to them, and serves as a species of keystone. Also, the weight or engagement of the tier of blocks above Y 10 and Z would prevent them from dropping. The workman can knock out as many blocks as necessary, and then reinsert new blocks.

Where hanger engaging blocks are removed, enough space has to be provided above the 15 hanger so that a new hanger block can be lowered into place on the hanger. The various blocks are positioned in place just as when the liner was under construction in the first place, except that when the workman comes to the 20 last block, and if a tongue and groove connection is employed, he has to knock off the tongue of the last block and the tongue of the block adjacent to it, to permit the last block to be inserted into the aperture left for it. In connection with inserting and removing blocks, it is important that the width of the outer face portion 16 be somewhat smaller than the width of the aperture to be filled by the block and closed by the inner face portion 15.

In the particular stack structure shown in Figures 1 and 2, outside air is admitted through the elbows 7 and through any suitable passages 7a into the interior of the air lane. Any suitable apertures in the top blocks may be provided to admit this air. The air then blows downwardly through the air lane and out through the bottom passages 5 into the hot air collecting header 4.

It will be realized that whereas I have described and shown a practical and operative device, and a practical and operative form of block, nevertheless many changes may be made in size, shape, number and disposition of parts without departing from the spirit of my invention. I therefore wish my description and drawings to be taken as in a broad sense illustrative or diagrammatic, rather than as limiting me to my precise showing.

In particular, it will be realized that whereas I have shown blocks formed for use in a stack of generally cylindrical cross section, similar blocks may be employed to a rectilinear wall structure. The tongue and groove connection is preferable but is not under all circumstances necessary. The details or shape of the blocks can be considerably varied and hangers of varying form may be employed. It is important, however, that the hangers be so formed as to provide support for the blocks and to prevent inward displacement of the blocks. It will be understood also that my structure may be employed in connection with a wide variety of different designs of stacks and the like, and the direction of air flow may be varied.

The arrangement shown in Figure 1 provides for an air intake at the top of the stack and a discharge of the pre-heated air at or near the bottom. This arrangement might be reversed and, in fact, the inlet and outlet passages to the 70 pre-heating zones within the stack might be so arranged as to cause circulation in any direction desired.

Whatever the arrangement of the air inlet and air outlet, the pre-heating effect is increased by 75

the staggered relationship of the blocks and particularly of the connectors 17. This is illustrated in detail in Figure 7 and indicates that the air in passing through the pre-heating portion of 5 the stack must take a tortuous path following the air lane 10. This has the advantage of giving to the air a "scrubbing" action. In other words, the air in passing moves or "scrubs" against the connectors. Experience has shown that the air 10 is more readily heated by its impingement or "scrubbing" than by radiation or otherwise. Where the passages are straight or only slightly inclined or curved, it is possible for relatively quiet zones to develop and these zones form in effect 15 insulation so that the main body of the air is not effectively heated. The staggered relationship shown prevents the formation of these relatively quiet zones and compels the impingement or "scrubbing" action.

20 The connectors are relatively stream-lined to avoid undue resistance and by means of this stream-lining the area of hot refractory exposed in the air lane is thereby greater than the inner face area of the blocks exposed to the hot gases 25 in the chimney or furnace. The result of this design is to make a refractory heat exchanger of special efficiency and to reduce the tendency of the lining to burn out by maintaining the block at a temperature at which its mechanical strength 30 is perfectly adequate for the strains to which it is submitted, and further reducing the strain set up due to expansion and contraction through heating and cooling.

I claim:

35 1. As a new article of manufacture, a refractory block for furnaces or the like which includes an outside face portion, an inside face portion, and a connecting spacer portion between the said two portions of substantially smaller cross section 40 than either, the length of said spacer portion being substantially greater than the thickness of the outside and inside face portions, the outer faces of the two portions being arcuate and generally concentric, the face of the inside face 45 portion extending through a substantially greater angle of arc than the face of the outside face portion.

2. As a new article of manufacture, a refractory block for furnaces or the like which includes 50 an outer portion, an inner portion, and a connecting member connecting said portions, said outer portion and connecting member being provided with an aperture adapted to receive a supporting member, said aperture including a vertical portion parallel with the axis of the connecting member, and a transverse portion in communication therewith.

3. In a refractory block structure for furnaces and the like, an inner portion, an outer portion, 60 and connecting means therefor, said outer portion being provided with an aperture adapted to receive a supporting member, said aperture including a bottom recess, a vertical portion projecting upwardly therefrom and in communication therewith, and a transverse portion in communication with said vertical portion and recess.

4. As a new article of manufacture, a refractory block for furnaces or the like which includes 65 an inner face portion, and a radial connecting 70 spacer portion between the inner and outer portions, centrally located between the ends of the block, and of substantially smaller cross section than either the inner or outer face portions, and of substantially greater length than the thickness 75 of either the outer or inner portions, the inner

portion being of substantially greater width than the outer, measured transversely of the spacer.

5. As a new article of manufacture, a refractory block for furnaces or the like which includes an outer portion, an inner portion, and a connecting member centrally located between the ends of the block connecting said portions, said outer portion and connecting member being provided with an aperture adapted to receive a supporting member, said aperture being midway between the ends of the block.

6. In a refractory block structure, a pair of adjacent refractory blocks, each including an outside face portion, an inside face portion, and an integral connecting spacer portion between the two portions, and a separate spacer member interposed between the opposite edges of the outside face portions only, its outer face lying flush with the face of the outside face portion.

7. In a refractory block structure, a plurality 20 of refractory blocks, each such block including two separable parts, one superposed upon the other, each such part including an outside face portion, an inside face portion, and an integral connecting spacer portion between the two portions, and separate spacer members interposed between the opposite edges of the outside face portions only, said refractory blocks being arranged in generally arcuate arrangement, the outer faces of said spacer members being flush with the adjacent faces of said outside face portions.

8. In a refractory block structure, a plurality of refractory blocks, each such block including two separable parts, one superposed upon the other, each such part including an outside face portion, an inside face portion, and a connecting spacer portion between the two portions, and separate spacer members interposed between the opposite edges of the outside face portions only, said spacer members being each as high as the 40 adjacent refractory blocks, the edges of the adjacent inside face portions abutting, the outer faces of said spacer members being flush with the adjacent faces of said outside face portions.

9. In a refractory block structure, a plurality 45 of refractory blocks, each such block including two separate parts, one superposed upon the other, each such part including an outside face portion, an inside face portion, and a connecting spacer portion between the two portions, and 50 separate spacer members interposed between the opposite edges of the outside face portions only, said spacer members being each as high as the adjacent refractory blocks, the edges of the adjacent inside face portions of said block abutting, 55 said blocks and spacers being arranged in a plurality of superposed rows, the blocks and spacers of each adjacent row being staggered, whereby the separate spacer members of one row are supported upon the blocks of the row next 60 beneath.

10. In a refractory block structure, a plurality 65 of refractory blocks, each such block including two separable parts, one superposed upon the other, each such part including an outside face portion, an inside face portion, and a connecting spacer portion between the two portions, and 70 separate spacer members interposed between the opposite edges of the outside face portions only, said spacer members being each as high as the adjacent refractory blocks, the edges of the adjacent inside face portions abutting, the outer faces of said spacer members being flush with the adjacent faces of said outside face portions, and supporting brackets for said refractory blocks,

only a part of said blocks being so supported, the supported blocks being arranged in rows, with rows of unsupported blocks positioned above them, the blocks and spacer members of adjacent 5 rows being in staggered relationship, whereby the spacer members of one row are positioned upon the blocks of the row next beneath.

11. In a stack structure, an outside shell, a plurality of supports positioned upon the inner face 10 of said shell, and a lining for said shell including a plurality of refractory blocks, each such block including an outside face portion, an inside face portion, and a connecting spacer, some of said blocks being apertured to conform to said supports.

12. The structure of claim 11 characterized by the employment of a plurality of horizontal rows 20 of supports, the blocks of intermediate rows being supported upon the blocks engaged by said supports, the blocks of adjacent rows being staggered in relation to each other.

13. The structure of claim 11 characterized by the employment of a plurality of horizontal rows 25 of supports, the blocks of intermediate rows being supported upon the blocks engaged by said supports, the blocks of adjacent rows being staggered in relation to each other, independent spacing members being interposed between the opposed edges of the outside face portions of adjacent blocks, the linear width of the outside portion 30 of each block being slightly less than the linear width of the inside face portions of such block.

14. In a stack structure, an outside shell, a plurality of supports positioned upon the inner face 35 of said shell, and a lining for said shell including a plurality of refractory blocks; each such block including an outside face portion, an inside face portion, and a connecting spacer, the blocks being staggered within the stack to provide a tortuous air passage.

15. In a stack structure, an outside shell, a plurality of supports positioned upon the inner face of said shell, and a lining for said shell including a plurality of refractory blocks, each such block including an outside face portion, an inside face portion, and a connecting spacer, adjacent blocks being staggered with respect to each other. 5

16. In a stack structure, an outside shell, a plurality of supports positioned upon the inner face 10 of said shell, a lining for said shell including a plurality of refractory blocks, each such block including an outside face portion, an inside face portion, and a connecting spacer, the outer and inner face portions of the blocks establishing a pre-heating air passage, and means for introducing air to be pre-heated to said passage, and for withdrawing pre-heated air from said passage. 15

17. In a stack structure, an outside shell, a plurality of supports positioned upon the inner face 20 of said shell, a lining for said shell including a plurality of refractory blocks, each such block including an outside face portion, an inside face portion, and a connecting spacer, the outer and inner face portions of the blocks establishing a pre-heating air passage, and means for introducing air to be pre-heated to said passage, and for withdrawing pre-heated air from said passage, the blocks being staggered with respect to each other to bring adjacent spacers out of vertical alignment and to provide a tortuous air passage. 25 30

18. In a refractory block structure, a pair of adjacent refractory blocks, each including an outside face portion, an inside face portion, and an integral connecting spacer portion between the two portions, and a separate spacer member interposed between the opposite edges of the outside face portions only, the inside face portions of adjacent blocks abutting, the outer face of said spacer being flush with the outer face of said outside face portions. 35

40 MARK C. NEIL.
